UNITED STATES PATENT OFFICE.

LEWIS HALLOCK NASH, OF BROOKLYN, ASSIGNOR TO THE NATIONAL METER COMPANY, OF NEW YORK, N. Y.

GAS-ENGINE.

SPECIFICATION forming part of Letters Patent No. 289,693, dated December 4, 1883.

Application filed July 11, 1883. (No model.)

To all whom it may concern:

Be it known that I, LEWIS HALLOCK NASH, a citizen of the United States, residing at Brooklyn, in the county of Kings and State 5 of New York, have invented new and useful Improvements in Gas-Engines, of which the following is a specification.

The invention which I have made in the gas-engine is particularly directed to means 10 for preventing the heating of the piston and that part of the power-cylinder within which it operates to compress the air, so that the piston may work in a comparatively cool air-compression chamber, while the combustible 15 gases are burned in a very hot combustion-chamber, where the power is produced and the heat concentrated, whereby a great saving of the heat is effected; to a novel construction by which the gases are admitted into the cylinder 20 combustion-chamber, and in the construction by which a combustion-chamber is obtained to admit of a high temperature therein without materially increasing the heat of the other portion of the engine, wherein the piston and other 25 working parts operate; to the construction of a single-acting gas-engine cylinder, and the combination of a number of such cylinders so as to operate upon one crank, with suitable connecting mechanism for the pistons and for the 30 engine-valves and their controlling mechanism; and my invention comprehends a method of operating a gas-engine by liquid fuel and air, and of matters of construction and of combination which will be hereinafter described 35 and made the subject of specific claims.

The object of my invention is to produce a powerful and light gas-engine, specially adapted to operate dynamo-electric machines, and for other purposes.

40 In an application for a patent made by me March 19, 1883, I have described and claimed certain matters of invention in a single-acting gas-engine, by which the stored working-fluid is caused to envelop and pass over the heated 45 surface of the power-cylinder to cool the same; and I have therein shown and described a construction of cylinder by which the working-fluid is compressed by the forward stroke of the piston within the forward end of the cyl-

inder, and then discharged into a storage- 50 chamber.

In the present construction the air only is compressed within the forward end of the cylinder and discharged into a storage-chamber, and thence into an air-tight vessel placed 55 away from the engine, containing a volatile liquid fuel, which is thereby evaporated and the gas conveyed thence under pressure to the valve system for operating the engine.

In the combination of the three coaxing 60 cylinders, the air-storage chambers of each have perpetual communication, so that the degree of the force exerted by the compressed gases is alike at every point of the engine.

The accompanying drawings illustrate my 65 said invention, in which Figure 1 represents a transverse section of the engine, taken through the axis of three cylinders, and showing the piston crank-connections thereof. Fig. 2 represents a vertical section taken through the 70 line $x x$ of Fig. 1, showing one of the cylinders in axial section and its piston-rod crank-connections, the piston-rod of the cylinder shown in projection being removed and its crank-connections broken away. Fig. 3 represents a section through the valves, showing 75 their operating-connections and the position of the valves while the charge is being admitted into the combustion-chamber of the cylinder. Fig. 4 represents a similar section 80 of the valves, showing their position when the compressed air is discharged from the compression end of the cylinder into a storage-chamber surrounding the cylinder compression-chamber. Fig. 5 represents a similar 85 section of the valves, showing their position on the return-stroke of the piston. Fig. 6 represents a cross-section of the cylinder on the line 1 2 of Fig. 4, showing its communication with the valve-ports and the communication of the air-storage chamber with the valve-ports. Fig. 7 represents a cross-section 90 taken on the line 3 4 of Fig. 2, showing particularly the passage in the wall of the combustion-chamber of the cylinder to convey 95 the flame behind the piston. Fig. 8 represents a section taken on the line 5 6 of Fig. 6, showing the valves which control the admis-

sion of the fuel to the engine-valves and to the lighter jets. Fig. 9 represents a section of an air-tight storing-vessel, within which the liquid fuel is evaporated and from which the 5 gaseous fuel is supplied under pressure to the controlling-valves of the engine. Figs. 10 and 11 represent enlarged views of the piston crank-connections. Figs. 12 and 13 represent enlarged detail views of the reversing-gearing 10 of the engine. Fig. 14 represents the eccentric and its connection with the shaft for changing the point of cut-off. Fig. 15 represents a diagram showing the changes in the 15 point of cut-off of the gases entering the combustion-chamber, and the point at which the compressed gases from the compression-chamber enter the storage-chamber.

In the several figures of the drawings the same letters indicate the same parts, and I 20 have used the same letters to designate the three coacting cylinders, with numerical coefficients to indicate the several parts of each cylinder; and as the cylinders are of like construction and operation, it will be only 25 necessary to describe the operation of one or a part of any one to show the action of the same part in another cylinder.

The cylinders B' B' B' are arranged equidistant about a case, Z, upon which they are 30 secured in any suitable manner. The power-transmitting crank-shaft s is mounted in suitable boxes centrally within the case which encloses the crank K and the connections for the pistons and the valves. Each cylinder, as B', 35 has cast with it a surrounding storage-chamber, D', for the compressed air, and a chamber, W', for cooling-water at the forward end of said cylinder. Each cylinder forms an air-compression chamber, as C', at its forward 40 end, which communicates through its valves U' V' with the air-storage chamber D', while the latter communicates with the combustion-chamber A' through the air-tight vessel, and thence into the passage c' at the outer end of 45 said cylinder, upon which the combustion-chamber is mounted. The storage-chambers D' D' D' for the air or air and gas, when gas is compressed with the air of the several cylinders, communicate with each other through 50 a passage, d, preferably formed on the outer wall of the casing Z, as shown in Figs. 1 and 2, so that the pressure of the stored air is equal at all parts of the engine. Each cylinder has formed on its inner or forward end an 55 open part of less diameter than that within which the piston works, to form a bearing for the trunk or hollow rod R', which supports the piston P', and acts as a slideway for it. This smaller cylinder part has sufficient length 60 to form a good bearing and tight joint for the hollow piston-rod which opens into the chamber of the case. The water-chamber W' surrounds this bearing part for the piston-rod, and is arranged at the forward end of the cylinder 65 adjacent to the air-compression chamber C', and is supplied with water admitted

through the pipe p. (Shown in Fig. 2.) These chambers for water serve to keep the air-compression chambers C' C' C' cool, so as to work 70 well and to keep the air from being heated too much while being compressed without abstracting heat from the combustion-chambers. The water may be injected; or there may be a circulation, if desired, in which case there should 75 be an inlet and outlet pipe, p' p', as in Fig. 1. Each cylinder has mounted on its outer end and secured by bolts a hood or cap, J', having an interior diameter a little greater than that of the cylinder B', and forms the combustion-chamber A' of the cylinder. It is separated 80 from the open end of the cylinder by packing e' of some poor heat-conducting material—such as asbestos—to prevent the heat of the hood or cap J' from being communicated to the cylinder. 85

The piston P' has a suitable packing, and works within the cylinder proper, the depth of which is sufficient to allow for the stroke of the piston within it. A hood or hollow cap, 90 H', is secured to the piston P', and is also separated from the latter by a non-conducting packing, e'', to prevent the heat of said hood from being communicated to the piston. This piston-hood or hollow cap is of a diameter just sufficient to work within the cylinder without touching it, and to work within the cylinder-hood J' and leave a space, b', between it and the piston-hood when the latter is at the extreme of its outward stroke, which space 95 communicates with a flame-passage, c', around the inner edge of the base of the cylinder-hood J'. The gaseous charge is admitted by the valves U' V' into this space b', and passes back to the end of the cylinder-hood, so that the 100 combustible charge takes up the heat from these bodies, and its expansive force is thereby greatly increased. An enlarged passage, a', is formed upon the wall of the cylinder-hood J', which extends from the passage c' to 105 the closed end of said hood and opens into the combustion-chamber. This passage a' serves to convey the flame from the passage c' to the combustion-chamber behind the piston-hood when the latter is at the extreme of its outward stroke; and as, from the length of this 110 passage a', it will take some appreciable time for the flame to pass from the base-passage c' to the closed end of the hood J', a sudden explosion of the charge will thereby be prevented. The lighting of the charge is preferably effected by the electric wires m and n, which are insulated from each other and terminate in points within the passage c' in relation to the inflow of the gas, which I will 115 presently describe.

As the cylinder and piston-hoods will become greatly heated by the combustion of the successive charges, the hotter they become the less heat will be abstracted from the gases in 120 the power-cylinder before they do their work, and I prefer to cover the cylinder-hoods with 125

a non-conducting material, L, to prevent loss of heat from radiation.

The piston P' is supported by a rod, R', which has a rocking bearing upon the rod I', which is jointed at h' to the connecting-rods F' F' and to the swinging tie-rods E' E', the said rods F' F' making a bearing upon the crank-pin k, the rocking bearing being within the hollow stem of the piston, as described, 10 and for the purpose stated in my said application. The crank-pin k has sufficient length to connect with the several piston-connections of the engine.

Each cylinder is provided with controlling-valves, which are connected with and operated by the crank-shaft. The valves U' V' of the cylinder B' are connected with and operated by the rods x' y', connected with eccentrics X Y on the crank-shaft, as shown in Fig. 3. In this figure are also shown the rods x² y², which operate the corresponding valves of the cylinder B² by connection with the valve-rods x' y' while the valves of the cylinder B³ are operated by the connecting-rods x³ y³, also 25 jointed to the eccentrics; hence any change in the position of the eccentric X will affect the valves U' of all the cylinders in the same manner to change the point of cut-off and discharge of the gases, and a change in the position of the eccentric Y upon the same shaft will also affect all the valves V' to reverse the engine. The eccentrics are separate and independent in their action, each one performing a distinct function in operating the valves; 35 yet the combined action of the valves is necessary to operate the engine. The eccentric Y operates the valve V' for the full stroke of the engine, either forward or backward, in which operation of the eccentric Y and the 40 cut-off eccentric X need not be altered. The engine will then work either forward or backward and cut off at a fixed point.

If it is desired to change the point of cut-off, the position of the eccentric X must be 45 changed. Fig. 14 illustrates how this is done, in which the eccentric X is shown as having a slot fitting a flat part, s², of the shaft S, over and upon which the eccentric can be moved from the position X to the position shown by dotted lines X'. In the position X the center of the eccentric will be at o³, and will describe the circle 15 16, so that the engine will cut off at the point 23 of Fig. 15 and discharge the compressed gases from the chamber C' at 50 the point 24 of the stroke of the piston. If the eccentric be in the position X', its center o⁴ will describe the circle 25 26, and the engine will cut off at 29 and discharge the compressed gases from the chamber C' at the point 30, Fig. 60 15. The eccentric X may be set at any desired position and secured by a screw or other suitable means, and the point of cut-off may be altered at any time when the engine is not running by moving the eccentric into the desired position and securing it there.

In Figs. 12 and 13 I have shown in detail

the device for effecting this change of position of the eccentric Y in reversing the engine. The eccentric Y has a slot, s³, Fig. 12, by which it is fitted upon the end of the shaft s, so that it is free to be moved sidewise upon the shaft and is revolved by it. The eccentric Y may be moved from the position shown in full lines in Fig. 12 to that shown in the dotted lines Y', and the center o³ of the said eccentric is the position it should occupy when the engine is operating in one direction, and the center o⁴ of the dotted lines is the position the eccentric should occupy when the engine is running in the reverse direction. This lateral adjustment of the eccentric Y is effected by a feather, T, secured to it, and fitting into a groove, T', in a flat slide, o, which is adapted to be moved in the line of the shaft into and out of a slot, o', in the end of said shaft, as shown by dotted lines in Fig. 13. This adjustment of the slide o is effected by a screw, s², connected therewith by a swivel-joint, w⁴, so that by turning the screw s² to the right the slide o is moved into the position shown by dotted lines, and thereby the feather T will move the eccentric Y to the position shown by the dotted lines Y', which is the position of the eccentric for the reverse motion of the engine. The screw s² passes through a stuffing-box in a removable head, Z', of the case, and has a hand-wheel, W², by which to operate the slotted slide.

I have not shown any means for shifting the position of the eccentric X while the engine is running, because in many engines there is no necessity for altering the point of cut-off often, and the engine may be easily stopped to do this; but the eccentric X may be shifted by a device similar to that shown for shifting the eccentric Y.

The connections of the piston-rods with the crank-pin are shown in Figs. 10 and 11, and consist of straps t² t⁵, bolted together at each end, and between which are fitted two pieces of metal, t³ t⁴, which abut together at the middle of their length upon a taper key, t', as shown in Fig. 10, the meeting ends of said metal pieces being notched to receive said key between them, as shown in Fig. 11. The joint bearing h' of the piston connecting-rod and of the crank-pin k are at each end of the straps t² t⁵ and the metal pieces t³ t⁴, so that by driving in the taper key t' the pieces t³ t⁴ are caused to move into the bearings h k, and thus take up the wear of the parts. For this purpose the head of the taper key t' has a right-angled projection, through which a screw, t⁶, passes into a screw-tap in the metal piece t⁴, the straps t² t⁵ having slots to receive the key, and the screw passing through the slot of the strap t², as shown.

For lubricating the working parts and connections, oil is admitted into the case Z by any suitable oiling device, and I prefer also to inject water with the oil, to prevent the latter from becoming gummy.

The construction and operation of the valves will be understood from the following: Referring to the valves, they are arranged in suitable chambers side by side, and are operated 5 by the connections which I have described.

In the operation of valve V' the outlet-port 1 for the waste gases opens into the air at 14. Port 2 communicates with port 7 of the valve U'. Port 3 has free communication 10 with the air-storage chamber D'. Port 4 communicates with port 8 of valve U'. Port 5 opens into the compression-chamber C', as in Fig. 6, and port 6 opens into the air at 13, the said communication of port 3 with the air- 15 storage chamber being in a similar manner to that in which port 9 of valve U' opens into the storage-chamber.

In the operation of valve U' the ports 7 and 8 communicate with corresponding ports, 2 20 and 4, of valve V'. Port 9 communicates with the air-storage chamber D', Fig. 6. Port 10 opens communication between ports 8 and 9, and the upper end of valve U' opens and closes port 7. The valve V' has a port, 11, 25 which operates with ports 2 and 3, and a port, 12, which operates with ports 4, 5, and 6, while its upper end opens and closes the exhaust-port 1.

In the operation of the valves, the piston 30 being on its return-stroke, they will occupy the relative positions shown in Fig. 5, and the waste gases from the combustion-chamber will escape through the passage c' and the port 1 of valve V', and the air for the charge will 35 enter the compression-chamber C' at port 6 through ports 12 and 5. When the engine has completed its stroke, the valve V' closes ports 1 and 6 and opens communication between 40 ports 2 and 3 and between ports 4 and 5, the valve U' having already closed port 8 and opened port 7, so that the compressed air from chamber D' enters through passages 3, 11, 2, and 7 into passage c', and thence passes into the cylinder combustion-chamber A', around 45 the space b', and behind the piston-hood, which is then in position within and nearly filling the cylinder-hood, as shown in Figs. 1 and 2. At the instant of ignition the valve U' closes 50 port 7, Fig. 4.

The piston in its forward stroke compresses the air in chamber C' until it is at about the pressure of the air in the storage-chamber D', when the valve U' opens port 8, and thereby establishes free communication between chambers D' and C', through ports and passages 5, 55 12, 4, 8, 10, and 9, to the storage-chamber. Thus by the combined action of the valves U' V' the waste gases are discharged from the chamber A' through the whole stroke of the 60 piston, the charge of air is admitted into the compression-chamber C', the compressed charge is admitted into the combustion-chamber A', and the cut-off is effected at the desired instant of the stroke, while the compressed air from the chamber C' is admitted 65 to the storage-chamber D' at the latter end of

the stroke of the piston P'. This is effected by setting the valve V' to operate its ports during the full period of the stroke, and the valve U' to act as a cut-off valve for the entering charge, and to admit the compressed air from the chamber C' at the desired time. The point of cut-off and of discharge of the compressed air may be varied at pleasure by changing the throw of the eccentric X, as shown by 70 the diagram of Fig. 15, in which the circle 19 20 represents the path of the crank-pin, and the circle 15 16 the path of the center of the eccentric, and the line 17 18 the distance the valve U' travels between the point of 75 cut-off of the entering gases and the point where the compressed air is admitted to the storage-chamber D'. During the time valve U' is traveling this distance the crank-pin k will travel the arc 21 22, and the piston will 80 travel (not regarding the angular position of the connecting mechanism, for the purpose of illustration) the distance 23 24, the point 23 indicating the cut-off, and 24 indicating the point of the discharge of the compressed air 85 from the chamber C'. If, now, the position of the center of the eccentric is changed, so as to 90 describe the circle 25 26, the crank-pin will describe the arc 27 28 while the valve is traveling the distance 17 18, and 29 will be the 95 point of cut-off and 30 the point of the discharge of the air from the compression-chamber; hence changing the throw of one eccentric X changes the point of cut-off and of the discharge of the air from the compression-chamber. The air passes from the chamber C', 100 Fig. 6, to port 5, and from thence, through valve-port 12, Fig. 4, to port 4, and to port 8 of valve U', thence from port 8, through port 10, to port 9, it passes from port 9 to the 105 storage-chamber D'.

I propose to use the vapor of a volatile fuel—as gasoline—for operating the engine, and I prefer to control the admission of the gaseous fuel to the engine-valves from an air-tight storing-vessel, Z', by separate valves u' v', which are shown in Fig. 8. These valves are arranged in the case parallel with the main valves, and communicate with the supply-pipe G' and with the lighter or electric wires m n, and are operated by suitable connections with the main valves. The valve u' is operated by an arm, u', which is connected with the valve U', as in Fig. 2, and hence these valves will make the same movement. The valve v' is similarly connected to the valve V' by an arm, v', and both these valves make the same movement; hence the valve v' operates to open its port 5' throughout the full period of the stroke of the piston, while the valve u' operates to cut off the admission of the gas through the passage G' at the same instant that the air is shut off at port 7 by valve U'. In Fig. 8 the valves u' v' are shown in the position when the gas is being admitted to the cylinder.

The engine may be operated by means of any gaseous fuel supplied through the pipe G' un-

der pressure, and such supply is obtained from a suitable air-tight vessel, Z' , as shown in Fig. 9, which contains the liquid fuel. This vessel Z' connects by a pipe, p' , preferably at its bottom, with the storage-chamber D' , and conveys the compressed air from said chamber D' into the vessel containing the liquid fuel, which is thereby evaporated, the compressed air passing through the liquid fuel in the vessel, and thus producing a gaseous vapor under pressure stored in the vessel above the liquid fuel therein. A pipe, p' , connects this vessel at its upper part with the engine-supply pipe G' , and a cock, a' , controls the supply from said vessel, and may be operated by a governor, if desired. The gas under sufficient pressure passes from the vessel Z' and enters the pipe G' through the ports 5' 12' to the passage G' , from whence it passes into the cylinder-space c' and mingles with the air entering at port 7 of valve U' in relation to the electrical conductors, which I will presently describe. As the volatile fuel is evaporated by the compressed air passing through it, the vessel Z' must be constructed to withstand such pressure. The vessel containing the liquid fuel may be placed at any distance from the engine so as to be outside of the building in which the engine operates, if desired, and since only vapor enters the pipe p' there will be no danger from the use of any highly-volatile fuel. By this construction the air-storage chamber of the engine connects with a vessel containing a volatile fluid, and a portion of the air compressed by the engine is conducted into the working-chamber of the cylinder with the charge of gaseous fuel and a portion of the air conducted into the generator-vessel to produce the gaseous fuel; but it will be understood that the air only is compressed in the chamber C' , and is used as the means of evaporating the gasoline in the vessel Z' . I may, however, if found desirable, inject cooling-water with the air into the compression-chamber; or the engine may be operated by injecting liquid fuel within the compression-chamber C' , or by gas and air admitted into the compression-chamber, as described in my said application. When so operating the engine by compressing the charge in the chamber C' , the valves $u' v'$ and the vessel Z' will not be used, and it is obvious that my invention does not depend upon any particular means for supplying the working-fuel.

In connection with the arrangement of the valves $u' v'$ for controlling the supply of fuel to the engine-valves, it is important to notice that the electric wires $m n$ are placed at the outlet of the passage G' , and they should be so placed that one wire conductor, as m , is in the flowing stream of the fuel, while the other wire, as n , is just at one side of the gas-current from said passage, so that when the electric spark passes from m to n it will pass out from the gas into air, and hence have to cross the point where the gas and air are mingled at the edge or border of the gas-stream, thus effecting the lighting of the charge.

The relative positions of the valve-ports and passages shown in Figs. 3, 4, and 5 may be changed without changing the operation of the valves.

I do not propose to use cooling-water except in cases where the engine is developing great power and has become too hot for the piston and other working parts to be properly lubricated by the oil.

I may dispense with the hoods of the cylinder and of the piston, but prefer to use them for the purposes stated; and I may dispense with the piston-hood only.

The case Z is provided with a removable head, Z' , by which access may be had to the operating-connections of the valves and the pistons.

While I have shown and described a gas-engine of three connected co-operating cylinders and their valve-controlling mechanism, yet a single cylinder may be used with its valve system, and my invention is therefore not limited to an engine having three co-operating cylinders.

In case the electric spark is used to light the charge and the gas admitted at the back of the combustion-chamber, the flame-passage a' need not be used; but I prefer the construction shown.

A solid piston and the ordinary operating-connections may be used instead of the construction shown.

I claim—

1. The combination, in a gas-engine, of the cylinder having a hood or hollow cap forming the combustion-chamber, with the piston having a hood or hollow cap adapted to operate within the cylinder-hood, and to form a space therein surrounding the circumference and outer end of said piston-hood, and means, substantially such as described, whereby the combustible charge is admitted to said space in contact with the walls forming said space, substantially as described, for the purpose specified.

2. In a gas-engine, the combination of the cylinder having a hood or hollow cap forming the combustion-chamber, with a piston having a hood or hollow cap adapted to operate within the cylinder-hood, and a non-conductor of heat interposed at the junction of said hoods with their respective parts, as and for the purpose set forth.

3. In a gas-engine, the cylinder having a hood or hollow cap forming the combustion-chamber, provided with the ignition-passage c' at its junction with the cylinder opening into the combustion-chamber, as set forth.

4. The combination, in a gas-engine, of the cylinder having a hood or hollow cap forming the combustion-chamber, with a piston having a hood or hollow cap adapted to operate within the cylinder-hood and to form a surrounding space, b' , therein, the annular ignition-passage c' at the base of the cylinder-hood, and the flame-passage a' on the inner wall of said cylinder-hood, the said ignition and flame pas-

sages opening into the combustion-chamber, as set forth.

5. The combination, in a gas-engine, of the cylinder having a hood or hollow cap forming the combustion-chamber, with a non-conducting hood or cover enveloping said cylinder-hood, as set forth.

6. In a gas-engine, the combination of a cylinder, a storage-chamber for air under compression, and a chamber for cooling-water at the compression end of the cylinder, substantially as described, for the purpose specified.

7. The combination, in a gas-engine, of a power-cylinder in which the charge of air is compressed by the forward stroke of the piston, with a chamber for cooling-water arranged adjacent to the compression end of the power-cylinder, whereby the air-compression chamber is prevented from being unduly heated.

8. In a gas-engine, the combination of the cylinder, a surrounding storage-chamber for air under compression, a chamber for cooling-water at the compression end of the cylinder, and a guide-bearing for the piston-rod, surrounded by said cooling-chamber, with a piston having a hollow rod or trunk, substantially as described, for the purpose specified.

9. The combination, in a gas-engine, of the cylinder having a hood forming a combustion-chamber, a surrounding chamber, D', for air under compression, and a chamber for cooling-water at the forward end of the cylinder, with a piston having a hood adapted to operate within the cylinder-hood, substantially as described, for the purpose specified.

10. The combination, in a single-acting gas-engine in which the combustible mixture is ignited upon the back of the piston, and the charge of air is compressed by the forward stroke of the piston, of the valves U' V', and means, substantially such as described, whereby one valve is adapted to open its ports through the full stroke of the piston, and the other valve is adapted to cut off the inlet of the gases to the power-cylinder and to open communication with the air-compression chamber, substantially as described.

11. The combination, with the valve system of the engine, of the valves u' v', for controlling the charge of the gaseous fuel, the wires m n, and the passage G², having such relation to the said wires that one of them terminates within the flowing stream of gaseous fuel and

the other terminates at one side of said stream, 55 for the purpose specified.

12. The combination of the single-acting gas-engines and means for connecting the pistons of the several cylinders thereof, for co-operative action, with the storage-chambers for air under pressure, surrounding said cylinders, and a case inclosing the operating-connections, having a passage, d, communicating with the storage-chambers of the several cylinders, substantially as described. 65

13. The combination, with the piston of an engine and the power-transmitting crank-shaft, of an intermediate adjustable connecting-rod composed of straps t¹ t⁵, united at their ends, abutting pieces t³ t⁴, secured between said united straps, forming end joint-bearings, and an adjusting-key, t', passing through slots in the straps and between the abutting ends of the interior bearing-pieces, whereby the latter may be adjusted for taking up the wear of 75 the said joint-bearings.

14. The combination, with a gas-engine operating to compress its charge of air into a storage-chamber, of an air-tight vessel placed at a distance from the engine, containing a volatile liquid fuel, a pipe, p³, connecting said storage-chamber with the lower part of said separate vessel, a charge-supplying pipe, G², the supply-controlling valves u' v', and the main valves U' V', substantially as herein set forth. 80

15. The method substantially herein described of operating a gas-engine, which consists in compressing air in the forward end of the cylinder, passing it thence around the cylinder, and a portion of the air so compressed through a volatile liquid fuel contained within an air-tight vessel, and conducting under the pressure of the air the charge of gaseous vapor evaporated thereby to the valve system of the engine and to the electric wires for lighting the charge, which latter is completed by admixing therewith a separate charge of compressed air. 90

In testimony whereof I have hereunto set my hand in the presence of two subscribing witnesses. 95
